I claim the ornamental design for a frame molding for an entrance opening, as shown and described.

DESCRIPTION

FIG. 1 is a perspective view of a frame molding for an entrance opening showing my new design.

FIG. 2 is a front elevation view thereof.

FIG. 3 is a top plan view showing the side frames of a frame molding for an entrance opening in FIG. 1.

FIG. 4 is a side view of the top frame of a frame molding for an entrance opening in FIG. 1; and,

FIG. 5 is an enlarged top view of the right side frame in FIG. 3.

The broken lines are for illustrative purposes only and form no part of the claimed design.
